CARPET.

No. 15,486.

Patented Oct. 28, 1884.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,486, dated October 28, 1884.

Application filed August 6, 1884. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The design consists of the leaf-sprays, shown arranged evenly over the face of the design in

uniform but inconspicuous groups, and having no stem-connections, all as is clearly shown in the photograph, the interstices over the whole face of the design being irregularly traversed 20 by vein-work interblending with the leaves.

I claim—

1. The design for a carpet, consisting of the stemless leaf-groups, substantially as shown and described.
2. The design for a carpet, consisting of the stemless leaf-groups and the interstitial vein-work, substantially as shown and described.

JAS. L. FOLSOM.
